UNITED STATES PATENT OFFICE.

BENJAMIN F. NAGLE, OF READING, PENNSYLVANIA.

ELASTIC STIRRUP.

No. 895,291.

Specification of Letters Patent.

Patented Aug. 4, 1908.

Application filed October 11, 1907. Serial No. 396,957.

To all whom it may concern:

Be it known that I, BENJAMIN F. NAGLE, a citizen of the United States, residing at Reading, in the county of Berks and State of Pennsylvania, have invented new and useful Improvements in Elastic Stirrups, of which the following is a specification.

This invention is an improved yieldable safety stirrup in which the side members of the stirrup are pivotally connected to the arch and are connected together by a spring which enables them to move outwardly to widen the space between them and thereby enable said side members to adjust themselves to the width of the rider's foot and to release the rider's foot in the event that he should be thrown from his horse and thereby prevent the rider from being dragged; and the said invention consists in the construction, combination and arrangement of devices hereinafter described and claimed.

In the accompanying drawings: Figure 1 is an elevation of a stirrup constructed in accordance with my invention. Fig. 2 is a sectional view of the same. Fig. 3 is a horizontal sectional view of the same taken on the plane indicated by the line 3—3 of Fig. 1, and looking upwardly.

The side members 1 of my improved stirrup are pivotally connected at their upper ends as at 2 to the arch member 3. The said side members are provided on their inner sides, near their lower ends, with eyes 4, to which are connected the ends of a coiled retractile spring 5. Said side members are provided with inwardly extending studs 6 which operate in a bore in the foot piece 7 and are provided with stops, which depend therefrom and are indicated at 8, said stops operating in longitudinal slots on the underside of the foot piece.

It will be understood that the spring 5 forms a yieldable connection between the lower ends of the side members of the stud to move such side members toward each other and normally keep them in contact with the ends of the foot piece 7. When the stirrup is in use, the spring serves to keep the side members of the stirrup in contact with opposite sides of the foot of the rider and the stirrup hence will fit a foot of any size. In the event that the rider should be thrown, the spring will permit the side members to yield so that his foot will be released from the stirrup and thereby avoid all danger of his being dragged.

The side members 1 of the stirrup are provided at their upper ends with guard projections 10 which form stops that coact with the sides of the arch member to limit the inward movement of said side members while permitting them to move outwardly to any desired extent.

Having thus fully described the invention, what is claimed as new is:—

The herein described stirrup comprising an upper member, side members pivotally connected thereto and depending therefrom, said side members provided with inwardly extending studs, a foot piece having a bore engaged by the said studs, a spring connected to the said side members to move the latter normally toward each other and means to prevent casual detachment of the studs from the foot piece.

In testimony whereof I affix my signature in presence of two witnesses.

BENJAMIN F. NAGLE.
